W. T. CROUCH

NECKTIE ADJUSTER

Filed April 15, 1926

Inventor
W. T. Crouch.

By *Alfred Phelps Jr.*
Attorney

UNITED STATES PATENT OFFICE.

WALTER T. CROUCH, OF SAN ANTONIO, TEXAS.

NECKTIE ADJUSTER.

Application filed April 15, 1926. Serial No. 102,224.

The invention relates to neckties and has for its object the provision of an improved means for adjusting the necktie on the neck of the wearer, comprising a tubular member adapted to be secured to the necktie through which is threaded the ends of the strap that is looped below the tubular member, the neckband having its ends secured to the ends of the strap, and a clasp mounted on the looped lower end of the strap to hold the strap and neckband in adjusted position.

The invention will be described in detail hereinafter and will be found illustrated in the accompanying drawings in which—

Figure 1 is a front view of a necktie and neckband showing in broken lines the necktie adjuster in position on the necktie.

Figure 2 is a view in elevation of the necktie adjuster showing the strap in position therein,

Figure 3 a longitudinal sectional view on a plane indicated by the line 3—3 of Figure 2, and

Figure 4 a view in perspective of the tubular member to be secured to the necktie.

In the drawings similar reference characters will be used to designate corresponding parts throughout the several views.

The improved necktie adjuster is shown in Figure 1 attached to a necktie indicated A, the adjuster comprising a tubular member 1 that is adapted to be made from a single blank of sheet metal having portions

bent as shown at 2 to form a flat tubular portion 3, and a head 4 formed by bending the portions 5, 6, and 7 cut out from the sheet metal to form an opening 8 alining with the tubular member 3, and laterally

extending openings 9. Intermediate of the tubular portion 3 and the head 4 is an open portion 10 necessitated by the material required for the parts 5 and 6, and the material remaining after the parts 2 and 5 and

6 have been provided for, and designated 11 is bent rearwardly of the tongue forming the open portion 10 to strengthen said tongue. The member 1 is adapted to be secured in any suitable manner to the necktie

A, and threaded through said tubular member is a strap 12, the ends of said strap being threaded upwardly from the lower end of the tubular portion 3 and then

through the opening 8 into the head 4 and extended out through the openings 9. A neckband 13 has its ends secured to the ends of the strap 12 and is adapted to encircle the neck of the wearer to hold the necktie 4 in position thereon.

The lower end of the tubular member 1 is provided with a clasp including a tongue 14, extending downwardly from said member 1 and having outwardly extending ears 15, and 16 is a cam lever fulcrumed in said ears and adapted to clamp strap 12 that is threaded between the tongue 14 and said lever, it being apparent that strap 12 may be drawn downwardly by engaging the loop formed below the clasp and held in adjusted positions by means of the clasp.

What is claimed is:—

1. A securing device for neckties, comprising a member adapted to be secured to a necktie, said member including a vertical tubular portion and a tubular head having lateral openings and an opening alining with said tubular portion, a strap having its ends threaded upwardly through said tubular portion and through the opening in the head alined therewith and the ends of the strap extended through the lateral openings in the head, a neckband having its ends secured to the ends of the strap, a tongue extending from the lower end of the tubular portion, and means on said tongue to engage the strap to hold the neckband in adjustment on the neck of the wearer.

2. A securing device for neckties, comprising a tubular member adapted to be secured to a necktie, a head communicating with said tubular member having laterally extended openings, a strap having its ends threaded upwardly through said tubular member and head and its extremities extended through said lateral openings, the strap below the tubular member being looped, a neckband secured at its ends to the extremities of the strap, a tongue extending downwardly from said tubular member, and a cam lever fulcrumed on said tongue and engaging said strap to hold it in adjusted positions.

In testimony whereof I affix my signature.

WALTER T. CROUCH.
